HEIGHT MEASURING SCALE

Gene A. McAtee, St. Louis, Mo., assignor to Lee-Rowan Company, St. Louis, Mo., a corporation of Missouri

Filed Mar. 21, 1966, Ser. No. 1,560

Term of patent 14 years

(Cl. D52—6)

FIGURE 1 is a view in front elevation of the height measuring scale with a height indicator turned to one side;

FIGURE 2 is a view in side elevation of the measuring device taken from the right side of FIGURE 1 with the height indicator in the operative position;

FIGURE 3 is an enlarged fragmentary view of the measuring device in front elevation;

FIGURE 4 is an enlarged fragmentary view of the measuring device in rear elevation;

FIGURE 5 is a view in section taken on the line 5-5 of FIGURE 3.

The broken line portions in FIGURE 2 of the drawing are shown for illustrative purposes only. Some of the scale indicia has been omitted from FIG. 1 for convenience of illustration.

I claim:

The ornamental design for a height measuring scale, as shown and described.
